US0D1091709S

(12) **United States Design Patent** (10) Patent No.: **US D1,091,709 S**
(45) Date of Patent: ** Sep. 2, 2025

(54) **SCOOTER**

(71) Applicant: **Shenzhen Chitado Technology CO., LTD.**, Guangdong (CN)

(72) Inventors: **Dianxuan Zhang**, Shenzhen (CN); **Dengjin Zhou**, Shenzhen (CN); **Shiyuan Zheng**, Shenzhen (CN); **Fuqi Zhou**, Shenzhen (CN); **Huihai Zeng**, Shenzhen (CN)

(73) Assignee: **Shenzhen Chitado Technology Co. Ltd.**, Guangdong (CN)

(**) Term: **15 Years**

(21) Appl. No.: **29/845,462**

(22) Filed: **Jul. 7, 2022**

Related U.S. Application Data

(63) Continuation-in-part of application No. 29/767,258, filed on Jan. 21, 2021, now Pat. No. Des. 960,995.

(30) **Foreign Application Priority Data**

Dec. 4, 2020 (CN) 202030747540.2

CLAIM

The ornamental design for a scooter as shown and described.

DESCRIPTION

FIG. 1 is a perspective view of the scooter, showing our new design;

FIG. 2 is a front side view thereof;

FIG. 3 is a back view thereof;

FIG. 4 is a right side view thereof;

FIG. 5 is a left view thereof;

FIG. 6 is a top view thereof;

FIG. 7 is a bottom perspective view thereof; and,

FIG. 8 is a perspective view thereof.

The broken lines shown in the drawings represent portions of the article and form no part of the claimed design.

1 Claim, 8 Drawing Sheets
